CONVEYER

William B. Fleming, Columbus, Ohio, assignor to
The Jeffrey Manufacturing Company, a corporation of Ohio

Application July 30, 1935, Serial No. 33,850

11 Claims. (Cl. 198—171)

This invention relates to a conveyer, particularly of the type adapted to gather coal after it is shot down in a mine room.

An object of the invention is to provide a conveyer of the above mentioned type in which a hold-down roller is provided at the tail end which will permit free passage of bent flights.

Another object of the invention is to provide a conveyer of the above mentioned type in which a hold-down roller is provided at the tail end which roller is grooved to permit free passage of flight attaching rivet heads.

Other objects of the invention will appear hereinafter, the novel features and combinations being set forth in the appended claims.

Fig. 1 is a plan view of a conveyer comprising my invention;

Fig. 2 is a side elevational view of the device of Fig. 1;

Fig. 3 is an enlarged perspective view of the tail section of my invention;

Fig. 4 is a sectional view of the tail section taken on the line 4—4 of Fig. 1 looking in the direction of the arrows;

Fig. 5 is a side elevational view of the tail section of the conveyer of my invention; and

Fig. 6 is a transverse sectional view taken on the line 6—6 of Fig. 1 looking in the direction of the arrows.

Referring particularly to Figs. 1 and 2 of the drawings, there is seen a conveyer comprising my invention which is particularly adapted to be employed in a coal mine as a face or as a room conveyer. That is, this conveyer, when used as a face conveyer, will be placed near the face of a coal mine room, which face is cut and shot down, after which the shot-down coal is loaded onto the conveyer and by said conveyer delivered to room conveyers, which may be of the same construction, by which it is conveyed from the room onto appropriate mine cars, or the like.

The said face or room conveyer comprises a head section A, a tail section B and one or more intermediate sections C, which may be removably attached by angle and bolt clamp means 8 and 9. The number of intermediate sections C may be varied at will to determine the length of the entire conveyer. The three sections A, B and C cooperate to form a continuous trough 10 having a bottom plate 10', within which trough is adapted to travel a continuous chain 11 carrying material conveying flights 12. The head section A is provided with a drive shaft 13 which is driven from a motor 14 through a speed reduc-

tion mechanism 15 and chain and sprocket drive means 16.

The tail section B of the conveyer is provided with an adjustable shaft 17 carrying a sprocket 18 adapted to mesh with the chain 11. Appropriate chain tensioning means 19 are provided for maintaining proper tension on the chain 11 and providing for the slackening of said chain 11, whereby the links thereof may be disconnected to insert or remove links to vary the length thereof when the length of the entire conveyer is varied.

It may be noted that the head section A is provided with a diverging bottom wall 20 and a dividing plow or deflector 21, which plow 21 is positioned in advance of drive sprocket 22 carried on shaft 13. Said diverging bottom wall 20 and plow or deflector 21 are effective to free any material which may be caught under flight 12 as the flight approaches the shaft 13.

As best seen in Fig. 6 of the drawings, the return path of the chain 11 and the flights 12 beneath the trough 10 comprises a pair of wear strips 23, 23 which extend longitudinally of the trough 10 and adjacent the sides thereof. These strips 23 are attached to transversely extending pipes 11' which constitute supports for the intermediate sections C.

Referring particularly to Figs. 3, 4 and 6, attention is directed to the particular construction of the tail section B and more particularly to the construction of the hold-down roller 24. It has been found in practice that the flights 12 sometimes become bent as illustrated in Fig. 6 and, unless special means are employed, such as herein disclosed, the hold-down roller or a flight is apt to become broken when the bent flight attempts to pass under the hold-down roller. To obviate this undesirable feature, I provide the hold-down roller 24 with a pair of end sections 25, 25 which are frusto-conical and of reduced diameter progressively outward toward each end thereof.

As is well illustrated by Fig. 6 of the drawings, this particular construction of the roller will allow a bent flight 12 to pass thereunder without damage to the flight or the roller.

It will, of course, be obvious that the hold-down roller 24 is highly desirable to the end that the chain 11 and the flights 12 will be guided to the bottom of the trough as they emerge from the tail section B.

The flights 12 are most readily attached to the chain 11 by rivets 26 which co-operate with

wing links 27 of the chain 11, which rivets 26 have projecting heads.

Another feature of the hold-down roller 24 resides in the provision of a pair of circumferential grooves 28, 28 which allow free passage of the heads of rivets 26 under said hold-down roller 24. Between the grooves 28 the hold-down roller 24 preferably comprises a cylindrical section 29.

In addition to the elements above specifically described, it is evident that the tail section B comprises a box type frame 30 including a pivoted top cover 31, provided with handles 32 and reinforcing angle members, which is adapted to protect the shaft 17, the sprocket 18 and hold-down roller 24 from the coal as it is shot down from the room face.

In the operation of the device comprising my invention as a face conveyer, the conveyer is preferably placed near the face of a room in a coal mine after appropriate kerfs have been cut in said face. The coal is then shot down and in some instances the conveyer will be almost buried by the shot-down coal. The motor 14 may then be started and the conveying mechanism, including the chain 11 and the flights 12, will clear the trough 10 of filled coal and discharge it into another conveyer or any appropriate means for removing the coal. The additional shot-down coal will then be loaded into trough 10 by which it will be conveyed away as aforesaid.

Hold-down roller 24 will be operative to guide the chain 11 and the flights 12 to the bottom of the trough 10 as they emerge from the tail section B. As was above pointed out, the tapering or frusto-conical end sections 25, 25 of the hold-down roller 24 permit free passage of any bent flight 12 thereunder. The circumferential grooves 28, 28 also permit free passage of the projecting heads of rivets 26 thereunder. As the coal is discharged over the head section A of the conveyer, the diverging bottom wall 20 and the plow 21 guide the material to each side of the central drive sprocket 22 and free flights 12 of any particle of coal which is caught thereunder.

The particular arrangement of the sprocket 18, shaft 17, roller 24, trough bottom 10' and chain 11, is a feature of my invention and is provided to the end that the overall height of the conveyer will be maintained at a minimum to accommodate itself to a low vein mine. As best seen in Fig. 4, the shaft 17 and sprocket 18 are so positioned that the lower or return run of chain 11 is horizontal, or, in other words, said lower run extends tangentially from said sprocket 18. Trough bottom 10' is so positioned as to provide for this construction. This results in a minimum of friction between flights 12 and guides 23, which increases greatly the life of both. This arrangement of parts also provides for the positioning of bottom 10' in the lowest possible position for the purpose of maintaining a minimum trough height, as above mentioned. However, unless some hold-down means were provided for the upper run of the chain 11, it would not contact the trough bottom 10' as it emerges from tail section B, and coal would get caught under the flights 12. Hold-down roller 24 insures that the flights will contact the trough bottom 10' as they emerge from the said tail section B. It is also to be noted that the hold-down roller 24 is adequately protected from falling coal by the reinforced top 31 of said tail section B.

Obviously those skilled in the art may make various changes in the details and arrangement

of parts without departing from the spirit and scope of the invention as defined by the claims hereto appended, and I wish therefore not to be restricted to the precise construction herein disclosed.

Having thus described and shown an embodiment of my invention, what I desire to secure by Letters Patent of the United States is:

1. In a conveyer, the combination with a trough, of a continuous chain, flights carried by said chain, head and tail sprockets for said chain, a hold-down roller adjacent said tail sprocket adapted to guide said chain to a position on the bottom of said trough, said roller being of reduced diameter progressively outward toward each end to permit bent flights to pass thereunder.

2. In a conveyer, the combination with a trough, of a continuous chain, flights carried by said chain, head and tail sprockets for said chain, a hold-down roller adjacent said tail sprocket adapted to guide said chain to a position on the bottom of said trough, said roller being tapered to permit bent flights to pass thereunder.

3. In a conveyer, the combination with a trough, of a continuous chain, flights carried by said chain, head and tail sprockets for said chain, a hold-down roller adjacent said tail sprocket adapted to guide said chain to a position on the bottom of said trough, said roller comprising a cylindrical center portion, and end portions forming conical sections of reduced diameter progressively outward to each end to permit bent flights to pass thereunder.

4. In a conveyer, the combination with a trough, of a continuous chain adapted to travel substantially along the central longitudinal axis of the trough, flights attached at their centers to said chain by rivets having upwardly projecting heads, head and tail sprockets for said chain, a hold-down roller adjacent said tail sprocket adapted to hold said chain against the trough bottom, said roller having circumferential grooves adapted to permit free passage of said rivet heads and having outwardly tapering conical portions adapted to permit the free passage of bent flights thereunder.

5. A tail section for a conveyer comprising a frame having side walls, a shaft extending between said walls, a central sprocket on said shaft, a hold-down roller extending between said side walls forward of said shaft, said roller having outwardly tapered conical portions and a pair of centrally positioned circumferential grooves.

6. A tail section for a conveyer comprising a frame having side walls, a shaft extending between said walls, a central sprocket on said shaft, a hold-down roller extending between said side walls forward of said shaft, said roller having outwardly tapered conical portions.

7. A hold-down roller for a chain conveyer comprising a body having a central cylindrical portion, conical end portions of decreasing diameter from the center thereof toward the ends, said body being provided with circumferential grooves between the central cylindrical portion and the conical end portions.

8. A hold-down roller for a chain conveyer comprising a body having a central cylindrical portion, and conical end portions, said body being provided with circumferential grooves between said central portion and said end portions.

9. In a conveyer, the combination with a trough having side walls, of a continuous chain

- adapted to travel along the center of said trough, flights carried by said chain having arms extending laterally thereof, centrally positioned head and tail sprockets for said chain, and a hold-down roller extending between said side walls and positioned adjacent said tail sprocket having a central roller portion adapted to ride on said chain and guide it to a position on the bottom of said trough, said roller being constructed to 5 permit vertically bent arms of said flights to pass freely thereunder by having its ends beyond said central portion of reduced diameter.
10. In a conveyer, the combination with a trough, of draft means adapted to travel substantially along the central longitudinal axis of the trough, a tail sprocket for said draft means positioned centrally of said trough, a hold-down roller adjacent said tail sprocket adapted to hold 10 said draft means against the trough bottom, flights attached to said draft means and having 15 wings extending laterally to each side thereof, said hold-down roller having outwardly tapering portions adapted to permit free passage of upwardly bent flights thereunder.
11. In a conveyer, the combination with a trough, of draft means adapted to travel substantially along the central longitudinal axis of the trough, a tail sprocket for said draft means positioned centrally of said trough, a hold-down roller adjacent said tail sprocket adapted to hold 10 said draft means against the trough bottom, flights attached to said draft means and having wings extending laterally to each side thereof, said hold-down roller having a central substantially cylindrical portion adapted to ride on said 15 draft means and having portions of reduced diameter extending over the paths of said wings to permit bent flights to pass freely thereunder.

WILLIAM B. FLEMING. 20
